[57] **CLAIM**

The ornamental design for a packaging container, substantially as shown and described.

DESCRIPTION

FIG. 1 is a top, front perspective view of a packaging container showing my new design;

FIG. 2 is a view similar to FIG. 1 but in an open position;

FIG. 3 is a top plan view in a closed position;

FIG. 4 is a front elevational view thereof;

FIG. 5 is a side elevational view, the opposite side being a mirror image thereof;

FIG. 6 is a rear elevational view thereof; and

FIG. 7 is a bottom plan view thereof.
